WINDOW SASH

Edouard Clerk, Saint Hilaire, Quebec, Canada

Application January 29, 1948, Serial No. 5,131

5 Claims. (Cl. 189—76)

1

This invention relates to improvements in double glazed window sashes in which the edges of the inner and outer glazing panels are mounted in grooves formed in a resiliently compressible glazing strip which is compressed between inner and outer sections of a sectional sash frame to provide pressure contact between the glazing panels and the side walls of the glazing strip grooves in which the panels are mounted.

One object of the present invention is to provide an improved double glazed window sash of the character described in which the sections of the sash frame are designed and secured together in a novel manner which improves the pressure contact between the glazing panels and the side walls of the glazing strip grooves in which the edges of the panels are mounted.

Another object of the invention is to provide a double glazed sash of the character described in which the sections of the sash frame are detachably secured together in a manner which improves the insulating efficiency of the sash assembly.

Another object of the invention is to provide a double glazed sash of the character described in which the sections of the sash are detachably secured together by coupling dowels which are easily and quickly applied and removed.

Other objects, advantages and characteristic features of the invention will be more readily understood from the following detailed description of the preferred embodiment shown in the accompanying drawings, in which—

Fig. 1 is an elevational view of a double glazed sash assembly designed in accordance with my invention.

Fig. 2 is a fragmentary vertical sectional view taken substantially along the section line 2—2 of Fig. 1.

Fig. 3 is a fragmentary vertical sectional view of a frame section constituting one-half of the sash frame shown in Fig. 2.

Fig. 4 is a view similar to Fig. 3 but showing the frame section constituting the remaining half of the complete frame assembly shown in Fig. 2.

Fig. 5 is a sectional view of one of the dowels employed for securing the sash frame sections together in their assembled relation.

As shown in the drawings, my improved sash assembly comprises a pair of laterally spaced glazing panels 5 having their edges mounted in grooves 6 formed in a glazing strip 7 made of rubber or other resiliently compressible material.

2

The glazing strip 7 is confined under compression in a relatively wide glazing channel 8 formed by and between the half sections 9 and 10 of a sash frame 11.

Frame section 9 is substantially rectangular in outline and is composed of frame members of substantially L-shaped cross section secured together in end to end relation. As here shown each frame member of section 9 has one limb 12 disposed in a plane paralleling the glazing panels 5. This limb 12 comprises a relatively thin inner portion 13 and a relatively thick outer portion 14. The relatively thin inner portion 13 constitutes one side wall of the glazing channel 8. The relatively thick portion 14 projects inwardly beyond the thin portion 13 to provide a ledge 15 which forms the minor portion of the width of the bottom wall of glazing channel 8. A strip 16, of resilient material such as rubber, is fitted in a groove 17 formed in the thicker portion 14 of limb 12 adjacent the ledge 15. The remaining limb 18 of each frame member of sash section 9 extends inwardly across the adjacent outer edge of glazing strip 7 in spaced relation thereto. This limb 18 is provided with a lengthwise extending groove 19 which is serrated to provide longitudinally extending V-shaped ribs 20. Each limb 18 is also provided, adjacent its opposite ends, with drilled dowel-receiving openings 21.

The sash frame section 10 is also substantially rectangular in outline and is composed of substantially T-shaped frame members secured together in end to end relation. Each T-shaped frame member of sash frame section 10 is arranged with its head portion 23 lying in the plane paralleling the glazing panels 5 and its stem portion 24 extending inwardly over the adjacent edges of the glazing panels so that its surface 25 forms the major portion of the width of the bottom wall of glazing channel 8. Each stem portion 24 terminates in a V-shaped rib 26 which bears against the previously mentioned strip of resilient material seated in the groove 17 of the opposing frame member of frame section 9. The stem portion 24 of each T-shaped side member of sash section 10 is provided with an outwardly facing groove 27 opposing but spaced from the inwardly facing groove 19 formed in the limb 18 of the corresponding L-shaped frame member of sash frame section 9. This groove 27 is shaped to provide longitudinally extending V-shaped ribs 27a. That portion of the head 23 of each T-shaped frame member of frame section 10 which extends inwardly from stem portion 24 forms the

3

remaining side wall of glazing channel 8. The remaining part of said head 23 which extends outwardly from said stem portion is formed with a groove 28 containing a strip 29 of resiliently compressible material which is engaged by a V-shaped rib 30 formed on the inner edge of the limb 18 of the opposing L-shaped frame member of sash frame section 9.

The component parts of the sash described herein are assembled in the following manner:

The glazing strip 7 having the glazing panels 5 mounted therein is arranged between the complementary half sections 9 and 10 of the sash frame as shown in Fig. 2. The initial width of the glazing strip 7 is such that when frame sections 9 and 10 are fitted against opposite sides thereof, the grooves 19 of the frame members of frame section 9 will be slightly offset outwardly with respect to the opposing grooves 27 of the frame member of frame section 10. Suitable clamps (not shown) are applied to frame sections 9 and 10 to force them together to compress the interposed glazing strip 7 and to align the grooves 19 of frame section 9 with the opposing grooves 27 of frame section 10. Then, while the clamps are still in place, four locking dowels 32 are inserted through the dowel-receiving openings 21 of frame section 9 so that each dowel is fitted in the grooves 19 and 27 of opposing frame members of frame sections 9 and 10. The V-shaped ribs of grooves 19 and 27 decrease the area of frictional contact between the sash frame sections and the dowels 32 so as to enable the latter to be more easily slid into and out of said grooves. Each dowel is a sufficiently tight fit in the grooves in which it is inserted to hold the sash frame sections in their glazing strip compressing relation when the clamps previously referred to are removed. In this relation of the sash frame sections the resiliently compressible strips 16 and 29 are compressed by the engaging V-shaped ribs 26 and 30. The dowels 32 inserted between the opposing frame members at the top and bottom of the sash frame shown in Fig. 1 are dimensioned and arranged so that in their final position they lie between the drilled openings 21 through which the remaining dowels are inserted between the opposing sash frame members at the sides of the sash frame.

The dowels 32 may be of solid or hollow construction and may be formed of metal, plastic, or any other suitable material. As shown in Figs. 2 and 5, each dowel is preferably provided with a fabric covering 32a having a nap 32b.

Having thus described the nature of my invention and a preferred embodiment thereof, it will be understood that various modifications may be resorted to within the scope and spirit of the invention as defined by the appended claims.

I claim:

1. In a double glazed sash assembly, a sectional sash frame provided with a continuous glazing channel extending around the inner edge thereof, a resiliently compressible glazing strip fitted in and extending entirely around said channel, inner and outer glazing panels having their marginal portions fitted in grooves formed in the inner edge of said glazing strip, said frame being divided into two half sections, each having a central opening and having its marginal portions shaped to provide a side wall and a part of the bottom wall of said channel, corresponding dowel-receiving marginal portions of said frames being disposed in spaced overlapping relation to each other opposite and parallel to the outer edge of

the glazing strip and being provided in their opposing surfaces with dowel-receiving grooves extending the full length of said overlapping marginal portions and a dowel fitted in the grooves afforded by each pair of corresponding overlapping marginal portions of the frame sections, said dowels being insertable in and removable from said grooves by longitudinal movement thereof through openings provided in one of said frame sections.

2. In a double glazed sash assembly, a sectional sash frame presenting a continuous glazing channel extending around the inner edge thereof, a resiliently compressible glazing strip fitted in and extending entirely around said channel, inner and outer glazing panels having their marginal portions fitted in grooves formed in the inner edge of said glazing strip, one section of said frame being composed of L-shaped frame members joined together in end-to-end relation and the other section of said frame being composed of T-shaped frame members joined together in end to end relation, one limb of each L-shaped frame member being disposed to form part of one side wall of said channel and being shaped to form part of the bottom wall of said channel, the remaining limb of said L-shaped frame member being disposed opposite and in spaced relation to the outer edge of said glazing strip and being provided with a longitudinally extending dowel-receiving groove on the side nearest the glazing strip, each of the T-shaped frame members being arranged with its head portion lying parallel with said glazing panels and with its stem portion extending inwardly from the head portion to form the remaining part of the bottom wall of said channel, the outwardly facing sides of the stem portions of the T-shaped frame members being provided with longitudinally extending dowel-receiving grooves opposed to the first mentioned dowel-receiving grooves, that portion of the head of each T-shaped frame member which extends inwardly from the stem portion of said frame member being disposed to form the remaining side wall of said glazing channel and dowels interposed between the two frame sections so that each dowel lies partly within the groove formed in the stem of one of the T-shaped frame members and partly within the opposing groove formed in the opposing limb of one of the L-shaped frame members, each dowel being insertable in and removable from its associated grooves by longitudinal sliding movement thereof through openings provided in the frame section composed of L-shaped frame members.

3. A double glazed sash assembly as set forth in claim 2, in which the stem portion of each T-shaped frame member bears against a strip of resilient material fitted in an opposing limb of one of the L-shaped frame members which lies parallel with said transparent panes.

4. A double glazed window assembly as set forth in claim 2, in which the limb of each L-shaped frame member which extends across and in spaced relation to the outer edge of the glazing strip is fitted against a resilient strip arranged in a groove formed in the head of the opposing T-shaped frame member.

5. In a double glazed sash assembly, a sectional sash frame comprising two half sections, each having a central aperture and having its marginal portion shaped to define the side and bottom walls of a continuous glazing channel extending around the inner edge of the frame, each

marginal portion of one of the frame sections being formed with a full length, inwardly facing dowel-receiving groove opposed to but spaced from a full length, outwardly facing dowel-receiving groove formed in the corresponding marginal portion of the companion frame section and a plurality of dowels securing said frame sections in assembled relation, each dowel being fitted in the opposing grooves of corresponding marginal portions of the frame sections and being insertable in and removable from said grooves by longitudinal movement of the dowel through openings provided in one of said frame sections.
